We claim the ornamental design for an endoscope, as shown and described.

DESCRIPTION

FIG. 1 is a perspective view of an endoscope showing our new design;

FIG. 2 is a front view of the endoscope;

FIG. 3 is a rear view of the endoscope;

FIG. 4 is a left side view of the endoscope;

FIG. 5 is a right side view of the endoscope; and,

FIG. 6 is a cross-sectional view of the endoscope taken along line 6-6 of FIG. 2.

The dash-dash broken lines illustrating portions of the endoscope are for environmental purposes only and form no part of the claimed design.

The dash-dot broken lines define the bounds of the claimed design and form no part thereof.
